UNITED STATES PATENT OFFICE.

ALBERT C. FRITZ, OF EVERGREEN PARK, ILLINOIS.

BURIAL VAULT.

Application filed March 7, 1924. Serial No. 697,590.

To all whom it may concern:

Be it known that I, ALBERT C. FRITZ, a citizen of the United States, residing at Evergreen Park, in the county of Cook and State of Illinois, have invented new and useful Improvements in Burial Vaults, of which the following is a specification.

This invention relates to caskets especially adapted for burial purposes.

10 An important object of this invention is to provide a burial casket wherein an inner layer of sheet metal is surrounded by an outer layer of cement and wherein a slow drying composition is arranged between the

15 layer of sheet metal and the cement to firmly unite the cement and the layer of sheet metal to provide an absolutely impervious structure and one which will positively exclude dampness and insects of various kinds.

20 A further object is to provide a burial casket having a novel form of connection between the cover and the body, which cover will be absolutely moisture and insect proof.

25 A further object of the invention is to provide a burial casket which is of highly simplified construction, neat in appearance and cheap to manufacture.

30 Other objects and advantages will be apparent during the course of the following description.

In the accompanying drawing forming a part of this application and in which like numerals are employed to designate like parts throughout the same,

35 Fig. 1 is a plan view of the improved casket with the cover applied;

40 Fig. 2 is a vertical sectional view taken on line 2-2 of Fig. 1;

Fig. 3 is a detailed sectional view illustrating the means to connect the cover to the body;

Fig. 4 is a sectional view, the cover being elevated and the view being taken on line 4-4 of Fig. 1.

45 In the drawing wherein for the purpose of illustration is shown a preferred embodiment of the invention, numeral 5 designates a sheet metal lining arranged in the form of a coffin and having side walls, the upper edges of which are extended outwardly and are formed with channels 6 for the reception of a continuous tongue 7 of the metal lining 8 of the cover 9. The lining 5 is completely surrounded by a con-

crete body 12 and a slow drying composition 14 is confined between the concrete body 12 and lining 5 and when this composition dries it firmly unites the concrete body with the lining and positively prevents the entrance of moisture. The composition 14 is preferably formed of linseed oil, tar, white lead and asphalt and when it dries it forms a hard layer which adheres to the metallic lining 5 and the concrete body. As the linseed oil gradually dries it enters the concrete body 12 and thereby renders the same impervious to moisture.

50 Particular attention is directed to Fig. 5 which illustrates that the upper edge of the concrete body is protected by a transversely curved cover strip 20 having an angularly projecting flange 22 which is imbedded in the cement and which flatly engages the outer wall of the channel member 6 whereby to completely conceal and protect the upper edge of the cement or concrete body.

55 The cover 9 is in the nature of a concrete body and is securely joined with the metallic lining 8 by means of a plastic composition 24 of linseed oil, tar, white lead and asphalt and this composition will take quite a while to dry. The linseed oil before drying will penetrate the concrete body 9 and therefore render the same absolutely water proof.

60 As illustrated in Figs. 3 and 4 the metal 10 is formed with a downwardly projecting 90 bend defining a tongue 7 and with an upwardly projecting bend to define the combined reinforcing and attaching flange 30. It is, however, to be noted that the flange 30 is curved transversely and is imbedded 95 in the concrete cover 9 so as to securely anchor the lining 8 to the cover.

65 The edge portion of the metallic lining 8 is transversely curved as indicated at 32 to conform to the curvature of the cover member 20 so that the casket will be securely sealed when the cover is applied.

70 In use a slow drying plastic is placed in the channel member 6 and the entrance of the tongue 7 into the channel member will cause a portion of the plastic to squeeze out between the cover plate 20 and the edge portion 32 and lodge there so as to form a secure seal.

75 When the cover is applied the air pressure will be around twenty or thirty pounds and will act to force the slow drying plastic

to a position between the cover plate 20 and the edge portion 32. This positively excludes dampness that causes the remains placed in the coffin to be preserved for an indefinite period.

In carrying out the invention a continuous reinforcing rod 40 is arranged beneath the transversely curved anchoring flange 30 and a plurality of openings 41 are arranged 10 in the concrete body 9 to allow hooks 42 to be connected to the reinforcing rod. The transversely curved anchoring flange 30 may be provided with openings in alignment with the openings 4.

15 Having thus described the invention, what is claimed is:

1. A casket comprising a concrete body, a sheet metal lining, for the body, a slow 20 drying composition arranged between the body and the lining the upper portion of the lining being provided with an outwardly arranged depending channel shaped member, and a cover plate arranged on the 25 upper edge of the body and engaged with the outer wall of the channel member and being provided with an anchoring flange imbedded in the concrete member.

2. A casket comprising a concrete body, a sheet metal lining for the body, a slow 30 drying composition arranged between the body and the lining the upper portion of the lining being provided with an outwardly arranged depending channel shaped member, and a cover plate arranged on the 35 upper edge of the body and engaged with the outer wall of the channel member, being provided with an anchoring flange imbedded in the concrete member and a cover having a continuous depending flange received in 40 said channel member.

3. A casket comprising a concrete body, a sheet metal lining arranged within the body and having its upper edge provided with a depending channel shaped member, 45 a cover plate mounted on the upper edge of the body and engaging the outer wall of the channel member, said cover plate being provided with an anchoring flange imbedded in the body, a plastic composition 50 between the lining and the body, and a cover having a lining provided with a depending tongue received in said channel member, said lining of the cover being provided with a transversely curved inwardly 55 extending anchoring flange overhanging said tongue and imbedded in the material of the cover.

4. A casket comprising a concrete body, a sheet metal lining arranged within the

body and having its upper edge provided 60 with a depending channel shaped member, a cover plate mounted on the upper edge of the body and engaging the outer wall of the channel member, said cover plate being provided with an anchoring flange imbedded in the body, a cover having a lining provided with a depending tongue received in said channel member, said lining of the cover being provided with an inwardly extending transversely curved anchoring 70 flange overhanging said tongue and imbedded in the material of the cover, and a reinforcing rod defined between said flange and said tongue.

5. A casket comprising a concrete body, 75 a sheet metal lining arranged within the body and having its upper edge provided with a depending channel shaped member, a cover plate mounted on the upper edge of the body and engaging the outer wall of the channel member, said cover plate being provided with an anchoring flange imbedded in the body, a cover having a lining provided with a depending tongue received in said channel member, said lining of the 80 cover being provided with a transversely curved anchoring flange overhanging said tongue and imbedded in the material of the cover, a reinforcing rod defined between said flange and said tongue, said flange being provided with spaced openings, and hooks 85 adapted for movement through said openings to engage said rod.

6. A casket comprising a concrete body, 90 a sheet metal lining arranged within the body and having its upper edge provided with a depending channel shaped member a cover plate mounted on the upper edge of the body and engaging the outer wall of the channel member, said cover plate being provided with an anchoring flange imbedded in the body, a cover having a lining provided with a depending tongue received in said channel member, said lining of the 95 cover being provided with a transversely curved anchoring flange overhanging said tongue and imbedded in the material of the cover, a reinforcing rod defined between said flange and said tongue, said flange being provided with spaced openings, hooks 100 adapted for movement through said openings to engage said rod, the outer edge portion of the lining of said cover being adapted to flatly contact with the cover 105 plate of the body.

In testimony whereof I affix my signature.

ALBERT C. FRITZ.
